[57] CLAIM

The ornamental design for a furniture leg, as shown and described.

DESCRIPTION

FIG. 1 is a perspective view of a furniture leg, showing my new design;
FIG. 2 is a side elevational view thereof;
FIG. 3 is an end elevational view thereof;
FIG. 4 is an elevational view, showing the end not shown in FIG. 3;
FIG. 5 is a side elevational view, showing the side not shown in FIG. 2;
FIG. 6 is a top plan view thereof;
FIG. 7 is a bottom plan view thereof;
FIG. 8 is a side elevational view of a furniture leg, showing a second embodiment of my new design;
FIG. 9 is an end elevational view thereof;
FIG. 10 is a top plan view thereof;
FIG. 11 is a bottom plan view thereof;
FIG. 12 is a perspective view of a furniture leg, showing a third embodiment of my new design;
FIG. 13 is a side elevational view thereof;
FIG. 14 is an end elevational view thereof;
FIG. 15 is an elevational view, showing the end not shown in FIG. 14;
FIG. 16 is a side elevational view, showing the side not shown in FIG. 13;
FIG. 17 is a top plan view thereof;
FIG. 18 is a bottom plan view thereof;
FIG. 19 is a side elevational view of a furniture leg, showing a fourth embodiment of my new design;
FIG. 20 is an end elevational view thereof;
FIG. 21 is a top plan view thereof;
FIG. 22 is a bottom plan view thereof;
FIG. 23 is a perspective view of a furniture leg, showing a fifth embodiment of my new design;
FIG. 24 is a side elevational view thereof;
FIG. 25 is an end elevational view thereof;
FIG. 26 is a elevational view, showing the end not shown in FIG. 25;
FIG. 27 is a elevational view, showing the side not shown in FIG. 24;
FIG. 28 is a top plan view thereof;
FIG. 29 is a bottom plan view thereof;
FIG. 30 is a side elevational view of a furniture leg, showing a sixth embodiment of my new design;
FIG. 31 is an end elevational view thereof;
FIG. 32 is a top plan view thereof; and,
FIG. 33 is a bottom plan view thereof.
